VARIABLE INDUCTANCE DEVICE

Vladimir J. Polydoroff, Chicago, Ill., assignor to
 Johnson Laboratories, Inc., Chicago, Ill., a corporation of Illinois

Application July 1, 1931, Serial No. 548,171

5 Claims. (Cl. 171—119)

The invention comprehends an inductive tuning device, composed of an inductance coil and a core of finely-divided magnetic material having insulated magnetic particles, suitable for use in high-frequency selective circuits. More specifically, the said device may be found advantageous when applied as an inductive coupling device between an antenna and the receiving circuit of a radio-receiving apparatus. Magnetic cores 5 of the type herein contemplated are described in my copending applications Serial Numbers 523,112 and 609,159, and in various publications both in the United States and abroad.

The invention will be better understood if reference is made to the accompanying drawing, wherein—

Figures 1, 2 and 3 show various embodiments of the invention;

Figure 4 shows a wiring diagram of a circuit embodying the invention, and

Figure 5 indicates operating characteristics of the circuit shown in Figure 4.

Figure 1 shows one variation of the invention, wherein a movable magnetic compressed core 1 is shown in partially engaged position over a coil 2, wound on a tube 3. On the same tube is wound a high inductance coil 4, terminals from both coils being secured to the soldering lugs 5. Figure 2 shows substantially the same arrangement, excepting that the coil 4 is wound inside of the tube 3.

When the coil 2, due to alteration of the core position relative to the coil, changes its inductance to such an extent that it produces the wide variation necessary to cover a certain band of frequencies, the coil 4 is inductively affected by the core only when the core is almost fully engaged with the coil.

It is a well known fact that antenna tuning may be accomplished by inductively coupling an un-tuned antenna to a tuned circuit, such as is shown in Figure 4, wherein 4 is the antenna coil, 2 is the inductance, 8 is the capacitance of a tuned circuit 9, and 10 is an audion, and wherein tuning to a desired frequency may be accomplished, either by variations of the capacitance 8 or of the inductance 2. Variations of inductance may be effected by moving the core 1, and tuning may also be accomplished by variations of both the capacity and the inductance of the circuit. Because of varying characteristics of the antenna and the circuit 9 at different frequencies, the potential delivered to the grid electrode of an audion 10 varies greatly with frequency variations.

If the circuit 9 is tuned by an iron core 1, and

the inductance and resistance of the circuit are changed in such a manner that the ratio

$$\frac{L}{R}$$

is kept constant throughout the frequency band, the potential delivered to the grid of the audion 10 will still vary, but to a considerably lesser degree than it would if the circuit were tuned by varying the capacitance 8.

To compensate for these variations of potential with frequency, it is possible to employ in the antenna coil 4 a large number of turns so that the whole antenna circuit is made resonant at a frequency somewhat lower than the lowest frequency to which the circuit 9 may be tuned. In that case and when said circuit is tuned throughout the entire range of frequencies with a constant input E. M. F. at the antenna, the ratio of potential delivered to the audion 10, to the constant E. M. F. applied to the antenna, represents the total gain of potential in the antenna and the tuned circuit, and may be graphically represented by curve *a* of Figure 5, where the range of frequencies is taken for the abscissa. This curve shows a small gain at high frequencies, which is gradually increased as the antenna circuit approaches the resonant conditions which occur somewhere below the lowest frequency of the circuit 9.

Curve *b* of Figure 5 shows one feature of the present invention, wherein the influence of the iron core, approaching the coil 4, starts to shift the resonant peak of the antenna circuit towards lower frequencies, resulting in a gradual decrease of the gain as compared with curve *a*.

This mode of operation is particularly pronounced in an inductive tuning device, such as is shown in Figure 3, wherein the core 1 is of the inner plug type, and wherein, as the core moves inside the coil 2, and approaches the coil 4, the inductance of the latter increases and the resonant peak of the antenna circuit is shifted to lower frequencies. Because of inadequate permeability of the central plug-type core, a metallic shielding ring 7, supported by insulating supports 6, may be added to the core, to thereby decrease the initial inductance of the coil by the well known short-circuiting effect, this effect being at its maximum when the ring 7 is in the middle of the solenoidal coil 2, the short-circuiting effect being decreased when the ring is moved to the right in the drawing. At the same time the core, being moved into the coil 2, produces an increase of the inductance. Thus, the total variation of the inductance from its

minimum value, with the ring in the center of the coil 2 and the core all the way out, to its maximum value, when the ring is entirely out of the coil and the core is all the way in, is sufficient to cover the entire broadcast-frequency range. The said ring may be irregularly shaped as shown to produce desired inductance variations.

Referring to Figures 1 and 2, it is evident that the inductance variations of the coil 4, as shown in these figures, are not quite sufficient to produce a substantially constant gain of the antenna coupling system within the frequency range.

However, another effect takes place when a core having a substantially closed magnetic field is used, as shown in Figures 1 and 2. The inductive transfer of energy from the antenna of Figure 4 to the circuit 9 is at its maximum when the coil 2 is out of the core 1. When the core is moved on the coil, the turns of the coil 2 which are adjacent to the core 1 become shielded by the core from the action of the coil 4, the shielding effect being at its maximum when the core is all the way in.

In other words, at the high-frequency end of the frequency range, when the antenna efficiency is lowest, the transfer of energy is greatest, and at the lower frequencies, when the antenna efficiency approaches the peak, the transfer of energy is reduced to a minimum. These two effects counter-balance each other throughout the range of frequencies to such an extent that it is possible to reduce the inductance value of the coil 4, so as to improve the gain at the high frequencies.

In such event, the gain variation of the system is as represented by curve c of Figure 5, and approaches a straight line.

Having thus described my invention, what I claim is:

1. A variable inductance device including a transformer and a magnetic core having insulated magnetic particles movable relatively thereto, said transformer having a solenoidal winding and a concentrated high-inductance winding fixed at one end of said solenoidal winding, the coupling between said windings being varied by

the relative movement of said transformer and said core.

2. A variable inductance device including a transformer and a magnetic core having insulated magnetic particles movable relatively thereto, said transformer having a solenoidal winding and a concentrated high-inductance winding fixed at one end of said solenoidal winding, the relative movement of said transformer and said core being such as to produce a considerable change in the inductance of said solenoidal winding and a comparatively slight change in the inductance of said concentrated high-inductance winding.

3. A variable inductance device including a transformer and a magnetic core having insulated magnetic particles movable relatively thereto, said transformer having a solenoidal winding and a concentrated high-inductance winding fixed at one end of said solenoidal winding, the relative movement of said transformer and said core being such as to produce a substantial change in the magnetic coupling between said windings.

4. A variable inductance device including a transformer and a magnetic core having individually insulated magnetic particles movable relatively thereto, said transformer having a solenoidal winding and a concentrated high-inductance winding fixed at one end of said solenoidal winding, the relative movement of said transformer and said core being such as to produce simultaneous changes in the inductance values of said windings and in the magnetic coupling between said windings.

5. A variable inductance device including a transformer and means movable relatively thereto, said transformer having a solenoidal winding and a concentrated high-inductance winding fixed at one end of said solenoid winding, said means including a magnetic core having insulated magnetic particles and a metallic ring spaced therefrom, the relative movement of said transformer and said means being such as to produce desired variations in the inductances of and in the coupling between said windings.

VLADIMIR J. POLYDOROFF. 120
